UNITED STATES PATENT OFFICE.

HIRAM O. COWDRICK, OF PHILADELPHIA, PENNSYLVANIA.

DESIGN FOR A BOOK-COVER.

SPECIFICATION forming part of Design No. 30,006, dated January 17, 1899.

Application filed December 19, 1898. Serial No. 699,768. Term of patent 7 years.

To all whom it may concern:

Be it known that I, HIRAM O. COWDRICK, a citizen of the United States, residing in the city and county of Philadelphia, State of Pennsylvania, have invented and produced a new and original Design for a Book-Cover, of which the following is a specification, reference being had to the accompanying drawings, forming part thereof.

10 The leading feature of my design for a book-cover is a flap having recessed ends and a pocket opposite to said flap.

Figure 1 represents a face view of a book-cover embodying my design. Fig. 2 represents a longitudinal section thereof on line xx , Fig. 1.

Referring to the drawings, A designates a book-cover, the same consisting of the pocket

B, the back portion C, and the flap D, the latter consisting of the sheet E, which is continuous of the portion C, and the sheet F, which is folded over the sheet E. The flap D is wider than the portion C, and the sheet F thereof has its ends formed with recesses G.

II designates tongues on the ends of the back portion.

Having thus described my invention, what I claim as new, and desire to secure by Letters Patent, is—

The design for a book-cover, substantially as shown and described.

HIRAM O. COWDRICK.
